[57] CLAIM

We claim the ornamental design for an ice cream maker, as
shown and described.

DESCRIPTION

FIG. 1 is a front, right side perspective view of an ice cream
maker showing our new design;

FIG. 2 is a top plan view of the ice cream maker of FIG. 1;

FIG. 3 is a front elevational view of the ice cream maker of
FIG. 1;

FIG. 4 is a left side elevational view of the ice cream maker
of FIG. 1, the right side elevational view being a mirror
image;

FIG. 5 is a rear elevational view of the ice cream maker of
FIG. 1; and,

FIG. 6 is a bottom plan view of the ice cream maker of FIG.
1.
